UNITED STATES PATENT OFFICE.

HOVEY B. STONEMAN, OF COUNCIL, IDAHO.

SAFETY FUSE.

Application filed May 22, 1922. Serial No. 562,724.

To all whom it may concern:

Be it known that I, HOVEY B. STONEMAN, a citizen of the United States, residing at Council, in the county of Adams and State of Idaho, have invented certain new and useful Improvements in Safety Fuses, of which the following is a specification.

The invention appertains to certain improvements in safety fuses for protecting 10 electrical circuits and devices generally, and has for its primary object to provide for one of a type adapted to be substituted for the usual taps or binding nuts on the terminals of a vacuum tube socket commonly employed in a wireless system and to otherwise of itself constitute the terminal for the attaching thereto of the current conductors leading to and from the socket.

With the foregoing and equally important 20 objects in view the invention resides in the certain novel and useful construction and arrangement as will be hereinafter more fully described, set forth in the appended claims and illustrated in the accompanying drawings, in which:—

Figure 1 is an enlarged perspective view of the conventional form of a socket for the reception of a vacuum tube, and of a preferred embodiment of the device as applied 30 thereto,

Figure 2 is an elevation of the improved safety fuse,

Figure 3 is a vertical section taken diametrically through the same, and

Figure 4 is a horizontal section taken on the line 4—4 of Figure 3.

Referring to the drawings, the preferred embodiment of the invention as shown therein comprises a tubular body 10, of an insulating material such as glass or the like, having circular metal discs or plugs 11 and 12 fitted into the opposite lower and upper ends of the bore thereof, and set within the same flush with the end edges. These discs 40 or plugs 11 and 12 are spaced apart as at 13 medially of the bore of the body at a distance suitable to prevent any and all possibility of an electric current arcing therebetween.

Coextensive with the bore of the body 10 is a strip of fusible metal 14 which is arranged to abut the wall of the bore of the body 10 and is held in such position by having its opposite end portions arranged or wedged between the wall of the bore and the peripheral edges of discs or plugs 11

and 12. The upper and lower discs or plugs 12 and 11 are formed to provide centrally disposed and aligned bores which are suitably screw threaded, the bore of the lower disc or plug 11 for the engagement on a usual terminal screw (not shown) secured in the terminal extensions or ears *a* of the form of the electric socket fitting *b*, and the bore of the upper disc or plug 12 for the engagement therein of a binding screw 15 for the attaching thereto of a circuit conductor *c*.

As shown in Figure 1 of the drawings, each of the several terminal extensions or ears *a* of the socket *b* will have one of the 70 fuse terminals applied thereto, and for the purpose, the threaded shanks of the usual binding screws (not shown) of these extensions or ears *a* will be threaded upwardly 75 thereof whereby the bores of the lower discs or plugs 11 of the fuse terminals will be engaged thereon after the manner of a nut or tap, when the circuit conductors *c* will have their free ends bared for clamped engagement under the heads of the binding screws 80 threaded downwardly of the upper discs or plugs 12 of the fuse terminals. It is to be noted that these fuses may be made for any desired current carrying capacity, such as 85 for $\frac{1}{2}$; $\frac{3}{4}$; 1; $1\frac{1}{4}$; $1\frac{1}{2}$; 2 or more amperes.

From the foregoing, it will be readily apparent that, while a preferred embodiment of the fuse terminal has been described and illustrated herein in specific terms and details of construction, arrangement and application, various changes in and modifications of the same may be resorted to without departing from the spirit of the invention, or the scope of the claims appended hereunto.

Having thus fully described the invention, what is claimed is:—

1. A terminal fuse comprising a tubular body of an insulating material, a fusible conductor strip coextensive with and positioned throughout against the wall of the bore of said body, spaced conductive means for closing the opposite ends of said body and having edge contact with the opposite ends of said fusible strip, means engaging within the conductive means at one end of said body for attaching it to the usual terminal of an electric socket, and means engaging within the conductive means to the other end of said body for the attaching of a circuit conductor.

2. A terminal fuse comprising a tubular

body of an insulating material, a fusible conductor strip coextensive with and positioned throughout against the wall of the bore of said body, spaced metal plugs at and within the opposite ends of bore of said body and having edge contact with the opposite ends of said fusible strip, the lower of said plugs having a threaded bore formed centrally adapted to engage over the usual terminal screw of an electric socket, and a binding screw threaded inwardly of the upper of said plugs and adapted to clamp thereunder the bared end of a circuit conductor.

15 3. A terminal fuse comprising a hollow cylindrical body of insulation, a fusible conductor strip extending lengthwise of said body, and a conductive plug positioned within said body at each end thereof and spaced from each other, said plugs engaging the ends of said strip for clamping it against the inner face of said body, one of said plugs having means for connecting therewith the terminal of an electric socket, and the other of said plug having means for connecting therewith the bared end of a circuit conductor.

20 4. A terminal fuse comprising a hollow cylindrical body of insulation, a fusible conductor strip extending lengthwise of said body, and a conductive plug positioned within said body at each end thereof and spaced from each other, said plugs engaging the ends of said strip for clamping it against the inner face of said body, one of said plugs having means for connecting therewith the terminal of an electric socket, and the other of said plug having means for connecting therewith the bared end of a circuit conductor.

25 5. A terminal fuse comprising a hollow cylindrical body of insulation, a fusible conductor strip extending lengthwise of said body, and a conductive plug positioned within said body at each end thereof and spaced from each other, said plugs engaging the ends of said strip for clamping it against the inner face of said body, one of said plugs having means for connecting therewith the terminal of an electric socket, and the other of said plug having means for connecting therewith the bared end of a circuit conductor.

30 6. A terminal fuse comprising a hollow cylindrical body of insulation, a fusible conductor strip extending lengthwise of said body, and a conductive plug positioned within said body at each end thereof and spaced from each other, said plugs engaging the ends of said strip for clamping it against the inner face of said body, one of said plugs having means for connecting therewith the terminal of an electric socket, and the other of said plug having means for connecting therewith the bared end of a circuit conductor.

35 7. A terminal fuse comprising a hollow cylindrical body of insulation, a fusible conductor strip extending lengthwise of said body, and a conductive plug positioned within said body at each end thereof and spaced from each other, said plugs engaging the ends of said strip for clamping it against the inner face of said body, one of said plugs having means for connecting therewith the terminal of an electric socket, and the other of said plug having means for connecting therewith the bared end of a circuit conductor.

40 8. A terminal fuse comprising a hollow cylindrical body of insulation, a fusible conductor strip extending lengthwise of said body, and a conductive plug positioned within said body at each end thereof and spaced from each other, said plugs engaging the ends of said strip for clamping it against the inner face of said body, one of said plugs having means for connecting therewith the terminal of an electric socket, and the other of said plug having means for connecting therewith the bared end of a circuit conductor.

the bared end of a circuit conductor, said plugs and the ends of said strips flushed with the ends of said body.

5. A terminal fuse comprising a hollow cylindrical body of insulation, a conductive plug arranged therein at each end thereof and having edge contact with the inner face of said body, said plugs spaced from each other and each having a bore formed with a threaded wall for connecting a conducting element therewith, and a fusible conductor positioned within said body and having its ends clamped between the outer edges of the plug and the inner face of said body.

6. A terminal fuse comprising a hollow cylindrical body of insulation, a conductive plug arranged therein at each end thereof and having edge contact with the inner face of said body, said plugs spaced from each other and having means for connecting conducting elements therewith, and a fusible conductor positioned within said body and having its ends clamped between the outer edges of the plugs and the inner face of said body. 65

7. A terminal fuse comprising a hollow cylindrical body of insulation, a conductive plug arranged therein at each end thereof and having edge contact with the inner face of said body, said plugs spaced from each other and having means for connecting conducting elements therewith, and a fusible conductor positioned within said body and having its ends clamped between the outer edges of the plugs and the inner face of said body, said plugs and the ends of said strip flushed with the ends of said body. 70 75

In testimony whereof, I affix my signature hereto.
